UNITED STATES PATENT OFFICE

2,641,467

GARAGE DOOR OPENER

George E. Reed, Pontiac, Mich.

Application March 7, 1951, Serial No. 214,285

1 Claim. (Cl. 268—75)

1

This invention relates to door opening devices, and more particularly a hydraulic door opening means having a self-contained circulating pump unit controlled by a semi-automatic switch capable of remote control operation. While the present invention is applied to a garage door it will be appreciated that my improved door operating construction and control means are applicable to other types of doors.

It is therefore among the objects of this invention to provide an electrically operated hydraulic door lift and release means operative through an operating cycle to an open position having an automatic cut-off and a release valve operative to effect closure of the door.

Another object is to provide a durable, low cost, easily installed electric driven door opener.

A further object is to provide a simple, low cost hydraulic pump in a self-contained fluid pumping system.

A still further object is to provide a door lift construction that is semi-automatic in operation and capable of being remotely controlled.

Other objects than those stated will appear upon an understanding of my invention gained from the following description when read in conjunction with the drawings in which like numbers refer to like parts in the different views.

In the drawings:

Figure 1 is a side elevation showing the present invention operatively connected to a garage door.

Figure 2 is a side elevation detail showing one lift cylinder, the control switch and the power unit.

Figure 3 is a detail section of the pump unit taken on line 3—3 of Figure 2.

Figure 4 is an elevation in partial section taken on line 4—4 of Figure 1.

Figure 5 is a schematic view of the electric circuit.

Figure 6 is a partial section taken on line 6—6 of Figure 3.

Figure 7 is a partial section taken on line 7—7 of Figure 3.

Figure 8 is a detail section of the lift unit piston head construction.

Referring now in detail to the drawings the device 10 of this invention is adapted for use with a door 11 swingingly mounted in a door opening 12 of a garage 13, or other building.

The building 13 is of conventional construction having side walls 14 inwardly of which the door jambs 15 are disposed at each side of the door opening 12 over which a doorhead member

2

16 extends. Disposed at the top of the door opening is a head stop 17 engageable with the top portion 18 of the door 11. Extending along the edges of the door 11 are flexible strips 19 which in cooperation with a similar bottom strip 20 provides a weather seal means effective when the door is closed.

The door 11 is dependently hung between the door jambs 15 by pivot plates 21 fixedly attached to opposite edges of the door by suitable screws 22 and pivotally mounted on suitable bolts or lag screws 23, carried by the jambs, with the plates spaced inwardly of the jambs by suitable bushings 23a. Each of the plates 21 are formed generally quadrilateral, as best shown in Figure 2, with the one side 24 secured to the door 11 as at 21a and are formed with a pivot or aperture 25 disposed adjacent the top edge 24a and spaced inwardly of the door 11. Thusly a pivot point 25 is provided at each side of the door 11 with said points being offset inwardly from the vertical centerline of the door and disposed above its horizontal centerline so as to effect a constant tendency for the door to swing to a closed position, as shown by dotted lines in Figure 1. Spaced from pivot points 25 and formed in each plate 21 in a downwardly disposed relationship to the first mentioned pivot with the door in a closed position is a second pivot aperture 26. The position of aperture 26 in the plates 21 provides thrust points for attachment of hydraulic lift or jack units 27 at each side of the door 11 as hereinafter explained.

Each of the jack units 27 is provided with a cylinder 28 having a dependent ear 29 adapted for pivoted mounting on the face of an adjacent door jamb 15 by a suitable bolt or lag screw as at 30 having a headed end 30a protruding from the jamb 15. The ear 29 is positioned outwardly from the jamb 15 to provide suitable clearance for passage of cylinder 28 past the jamb by a suitable bushing 31 carried by bolt end 30a; an elongated tension plate or bar 32 is disposed outside of each jack unit 27 as a fixed connector 45 extending between bolt end 30a and lag screw 23 at each side of the door. The weight of the door 11 acts upwardly on lag screw 23 and downwardly on bolt 30. The tension plate in this manner forms a strut or brace 32 connecting between the pivot points formed by bolts 23 and 30 which may be described as upper and lower points respectively, so that the bending moment upward of the upper subtracts from the greater bending moment downward of the lower, and thus acting 50 to cancel out or greatly reduce the stress on both

the pivots 23 and 30. Suitable spacers 31^a are provided under each end of each tension plate 32 to space it free of the jack cylinders 28 and allow for free movement of the cylinder past the plates.

The cylinder 28 of each unit 27, as best illustrated by Figure 2, is formed with a closed bottom end 33 tapped as at 34 to provide a fluid inlet 35 thereinto. Each cylinder 28 is formed with an opposite end 36 that opens toward plate 21 to receive a piston rod 37 which is fitted with a slightly loose piston head 37^a. Below 37^a is a self-aligning floating cup 38 preferably formed of rubber-like material so as to act as a continuous seal for the fluid pressure created in the cylinder 28 which, if any, is always upward in direction. This floating arrangement of the sealing cup 38 allows the door 11 to be lifted by hand without the necessity of pulling the sealing cup. In this manner any tendency of the piston to suck air into the cylinder is eliminated. With the piston rod 37 freely movable, the door 11 is adapted for hand lifting in case manual manipulation is desired for any reason. Around the piston rod 37 is fitted a circular guide member 39 removably secured as by thread engagement at 40 with the end 36 of cylinder 28. Each of the rods 37 is provided with a free end 41 adapted for rockable bolted attachment to plate 21 at pivot point 26. While I have described one lift unit 27 with its connecting pivot plate 21 in detail it will be readily understood that a similar unit and mounting at each side of the door 11, as best illustrated by Fig. 4, will provide a smooth even lift which is highly desirable.

Fluid pressure to the lift jacks 27 is supplied by an operating unit 42. The operating unit 42 is preferably mounted at one of the door jambs 15 slightly inside of the door pivots and is preferably disposed on the car driver's side of the door opening. This location aids in simplifying the automatic switch cut-off at the top of the door lift and of connecting the driver's yard control, as hereinafter explained. The unit 42 is conveniently formed with a common mount 43 adapted for bolted attachment as at 44 to a suitable vertical surface disposed adjacent the door top 18. Weld attached to the common mount 43, as best illustrated in Fig. 3, is a pump housing 45. The housing 45 is provided with a removable cover 46 held in place by suitable screw means as at 47. The one side 48 disposed away from the door opening 12 is apertured as at 49 to receive the shaft 50 of an electric motor 51. The motor 51 is secured to the mount 43 by a suitable number of bolts 52 and provides power suitable for operation of the fluid pump as hereinafter described.

Mounted on shaft 50 and secured thereto by a set screw 53, or the like, is a crankshaft 54 formed as an extension of the motor shaft for rotation within the housing 45. Crankshaft 54 is formed with a crankpin portion 55 eccentrically rotative relative to the axial centerline of shaft 50.

Suspensionally mounted on the crankshaft 54 at each side of the crankpin 55 and in spaced relation to each other are a pair of elongated pump support plates 56. The plates 56 are of sufficient length to provide a pair of top ends 57 disposed just under the cover 46 and a pair of bottom ends 58 spaced adjacent the housing bottom wall 59. Secured between the bottom ends 58 by a pair of stay bolts or pins 60 is a

pump base 61 formed as a metal block bored to provide a through channel 62 and formed with an upstanding nipple 63 bored to provide a passage 64 communicating with the through channel 61.

Fitted over the nipple 63 is a fluid pump cylinder 66. The cylinder 66 is preferably formed as a piece of thin wall brass tubing which can be easily burnished to a close sliding fit with a piston 67 mounted therein, and can then be pressed onto nipple 63. Nipple 63 is formed with an outside diameter sufficient to effect a tight pressed-on fit with cylinder 66. This type of construction saves much time over the ordinary method of lapping a piston to a close fit in a cylinder of conventional construction. The fastening method is much simpler than bolts or threads. The thinness of the tube is essential for easy burnishing, and for easy and secure press fitting over the nipple 63.

Piston 67 is formed with an upwardly opening socket 68 adapted to receive the radiused end 69 of a connecting rod 70. Rod 70 is formed with an upwardly opening yoke 71 disposed opposite from end 69 that is adapted for engagement with the crankpin 55. The piston 67 is formed with a flanged top as at 72 which provides an abutment for one end of a compression spring 73 disposed in encircled engagement with the pump cylinder 66 with the other end of the spring seated on the pump block 61. The spacing of the cylinder 66 from shaft 54 and the length of rod 70 are arranged to provide for downward movement of piston 67 against the urge of spring 73 on rotation of the crankpin 55 to effect cam-like engagement of the crankpin with yoke 71. Spring 73 is dimensioned to maintain the rod 70 in constant engagement between the pin 55 and the piston 67. With the spring action attained by the aforescribed mounting of the piston and cylinder, a simplicity and tightness is effected with no close fitting of parts being required; whereas the standard construction of a bolted connecting rod and a cap fitted on a piston wrist pin is complicated and requires many close and accurate fits between these various parts. A further advantage of the present construction is that a smaller piston is possible than could be used if a wrist pin were required. The utility of my construction is to effect an inexpensive small capacity, high pressure pump which may be driven by a small electric motor.

The channel 62 of the pump base 61 is threaded at one side of passage 64 as at 74 to receive an exhaust valve 75 having a movable member 76 that acts as a flapper in a one-way valve structure to close off the exhaust passage 78 formed in a seat member 79. The other end of channel 62 as at 83 is formed to provide a receiver for an inlet valve press-fitted therein and preferably staked in place. The inlet valve is formed with a circular valve seat member 80 that faces inwardly of the block 61. A movable inlet valve member 81 is disposed inwardly of said seat and a coiled compression spring 82 engages member 81 to urge it to a normally seated position. The inlet valve effected is adapted to provide a check valve operation so as to allow for passage of fluid through channel 62 into the pump under suction of the piston 67 on its spring urged upward movement, and to prevent return flow of fluid from the pump on its downward movement effected by the cam action of crankpin 55.

The exhaust fitting 75 is formed with a thread-

ed outlet 84 adapted to receive a suitable pipe fitting 85 of a pump connecting tube 86 formed generally U-shaped and adapted to conduct fluid upwardly from passage 62 under pressure. Tube 86 is provided with a suitable top fitting 87.

Disposed between the top ends 51 of the pump support plates 56 and secured thereto by suitable pin means 108 is a fluid distribution block 88 having a horizontal passage 89 adapted to threadingly receive a check valve 90 secured to fitting 87. Check valve 90 is provided with a sharply tapered passage closing member 91 urged outwardly of block 88 by a coiled compression spring 92 disposed between it and a stop 93 formed in passage 89 and is adapted to effect non-return of fluid pumped through tube 86.

Opening outwardly from passage 89 into the sump chamber 35 formed in housing 45 is a pressure relief valve 94 for operation at a predetermined fluid pressure to effect return of excess fluid to the sump. The relief valve is of conventional construction and is also operative to relieve the system from developing an excess pressure should action of the lift units 27 be unduly resisted as in the case of door 11 being locked, or frozen shut.

Block 88 is formed with a pair of outlet passages 96 and 97 adapted to receive suitable outlet fittings 98 and 99 extended through a suitable slot 152 formed in top 46 and fitted on the ends of fluid ducts 100 and 101 with each one of said ducts communicating with a respective inlet 35 of the lift units 27 by suitable piping and flexible connections not shown. Block 88 is also apertured downwardly to receive a release or control valve 102 disposed oppositely from fitting 98. Control valve 102 is provided with a bore 103 communicating with passage 89 having an upwardly opening seat 104. A valve stem 105 slightly less in diameter than bore 103 is slidably disposed therein and is formed with an enlarged tapered top end 106 seatable on seat 104 to normally close the bore against passage of fluid. The diameter of bore 103 and the outside diameter of stem 105 are proportioned to provide the rate of flow of fluid from the lift units 27 necessary to effect the speed of door closure desired which in most cases is a relatively slow movement whereby slamming of the door is avoided.

In order to assure that the stem end 105 will properly seat I provide a compression spring 107 having one end engaging thereagainst with its opposite end bearing against the inner end of outlet fitting 98. The valve stem 105 is of sufficient length to extend protrudingly from the valve body for contact by a cam operated arm 132 connected to a control means as hereinafter explained.

It is to be noted that the closure members of check valve 90, pressure relief valve 94, and fluid release valve 102 are steeply tapered, having an included angle of approximately 30°. This steep taper causes the valves to seat easily and hold securely so that there is no leakage when the door 11 is in the open position. Any leakage would be troublesome causing the door to close when not desired. Also the steeply tapered valves do not require lapping to make them fit tightly.

The entire pump assembly just described is floatingly carried by the crankshaft 54 for normal operation which provides for perfect alignment of the pump assembly with its driving means. For purposes of safety and to provide for the absorption of pump torque reaction and starting loads I provide a loose fitting connection between the

pump support 56 and the housing 45 by means of a torque pin 109 mounted transversely of the housing to pass through aperture 110 formed through the block 88 and support ends 57. The diameter of aperture 110 is relatively large relative to pin 109 to provide a loose fit therebetween so as not to interfere with the normal alignment of the pump with the crankshaft 54. Such construction allows for full utilization of the power output of the motor resulting in lower production and operation costs as a relatively small motor can be used to meet the power requirements of the instant device.

Attached to the housing 45 is a switch or control box 111 preferably formed of sheet metal and welded to the outside of the housing. Box 111 is formed with a horizontal wall 112, a vertical back extension 113 and a vertical side wall 116 having an upper edge 117 angularly disposed to provide an abutment extending at right angles to the back extension and angularly disposed from the vertical as best illustrated in Fig. 2. Removably secured to the horizontal wall 112 by a suitable bracket 113 and bolt 114 (Fig. 3) means is a vertical front wall 115. Extending between the extension 113 and the front wall 115 is a horizontally disposed sleeve 118 secured by a bolt 119 bolted through the extension and wall disposed in spaced relationship. Rockably carried by sleeve 118 is a switch carrier 120.

The carrier 120 is of sufficient length and width to rockably carry a switch 121 secured thereto adjacent a lower end 122 oppositely disposed from a protruding end 123 adapted for engagement by the door top 18. Extending from the carrier 120 is a projecting arm 124 positioned to engage with the edge 117 on rocking of the carrier to limit the upward movement of the protruding end 123 when not engaged by the door. Extending between the lower end 122 and the side wall 116 is a tension spring 125 for holding the carrier 120 in a normally forwardly rocked position. Switch 121 is preferably of the knife-blade type having a blade 126 pivoted at one end as at 127 adjacent the pivot point of the carrier 120 with a contact 128 spaced therefrom and disposed adjacent the lower end 122.

Extending through the housing 45 at a point below carrier 120 is a bushing in which is rotatably mounted a control crankshaft 130. Shaft 130 is of such length as to extend from a point vertically aligned with the release valve stem 105 to a point above wall 112 inside of the control box 111. Shaft 130 is formed with a cammed end 131 on which is rockably mounted a release bar 132 engageable with stem 105 to effect operation of release valve 102 on rotation of shaft 130. The release bar 132 is secured against removal by suitable key means as at 133. Release bar 132 is held against rotation about shaft 130 by an adjustable stop 150 carried by a ledge 151 attached to an inside wall of housing 45. Secured to the opposite end of shaft 130 is a control plate 134.

Control plate 134 is formed generally rectangular in shape with an extended end 135 that protrudes out of the control box 111 and is accessible for hand manipulation. The opposite end 136 of the control plate is apertured to receive a rotatable drilled sleeve 137 interiorly threaded to receive a locking screw 138 to secure the end 139 of an operating wire 140 thereto. Wire 140 is slidably carried in a flexible tube 141 terminantly secured to horizontal wall 112 by a suitable threaded bushing 142. The tube

141 is preferably filled with oil and extended underground to a remote point such as post 143 located outside of the garage or building 13 as shown in Fig. 1. The extended end of tube 141 is turned upwardly and secured to post 143 by a bracket 144. The outer end of the wire 140 is terminated in a cap or button 145 formed with an overhanging skirt 146 that fits over the end of the tube 141. This construction provides for weatherproofing of the tube 141 in a readily accessible means for controlling movement of plate 134 from outside of the building.

Plate 134 is also apertured at a point 147 disposed adjacent the top edge of the plate and is spaced above and toward end 135 to pivotally mount an arm 148 at one corner of a triangular arrangement of the pivot and lever points associated with the plate and effected by shaft 130, plate end 136 and arm point 147. The arm 148 is preferably formed of insulating material and extends from point 147 to a point above shaft 130 where it is pivotally connected to the free end 149 of the switch blade 126.

Switch 121 is connected in circuit with motor 51 by lead 150 connected to the blade contact 127, and lead 151 connected to contact 128, respectively.

In the operation of my device the housing 45 is filled to a point just below the motor shaft with suitable oil to operate the system and lubricate the working parts. Of course the door 11 will be initially in a closed position as shown in dotted lines of Fig. 1 which frees carrier 120 to move under urge of spring 125 to a position wherein arm 124 engages the box edge 117 with switch 120 open. Operation is effected by a person desiring to open door 11 pushing down on either the button 145 or the plate end 135. Force applied at either point is effective to rock plate 134 and swing switch blade 126 into engagement with contact 128 to close the circuit to motor 51. Starting of motor 51 pumps fluid from the sump 95 through passage 62, tube 86, passage 89, outlets 98 and 99, ducts 100 and 101 to the lift units 27. The lift units 27 lift the door 11 to an open position where the door top 18 strikes carried end 123 to rock switch 120 so that contact 128 is pulled away from blade 126. The door 11 is held open by the fluid held in the lift units 27 under pressure by check valve 90.

Closure of the door 11 is effected by reverse rocking of plate 134 to operate shaft 130 to cammingly engage release bar 132 with the release stem 105. Upward movement of stem 105 to unseat the tapered top 106 allows for release of fluid through bore 103 allowing the lift units 27 to lower the door 11.

Inasmuch as various embodiments of the present invention may be made without departing from the scope thereof, it is to be understood that all matter herein set forth, or shown in the accompanying drawings, is to be interpreted as illustrative and not in a limiting sense.

I claim:

A hydraulic lift for a pivoted door comprising crank means carried by the door, a hydraulic lift means operatively connected to said crank means, a pump means communicating hydraulic pressure to said lift means, power means operatively connected to said pump, said pump means having a pressure release valve, switch means in circuit with said power means, said switch being rockably supported and rockable from a circuit connecting position to a circuit disconnecting position, an extension member rockable with said switch and engageable with the door on movement thereof to an open position for rocking the switch to the circuit disconnecting position, a rockable lever, cam means operatively connected to said lever, said cam means being engageable with said release valve, connecting means between said lever and said switch for effecting circuit closure of the switch on rocking of the lever in one direction with said cam means engageable with said release valve on rocking of said lever in an opposite direction, and a remotely disposed means for rocking said lever.

GEORGE E. REED.
